ROOF DRILLING AND BOLTING MACHINE

John E. Long, Oak Hill, W. Va., assignor to Marmon
Group, Inc., Chicago, Ill.

Filed Mar. 4, 1971, Ser. No. 121,227

Term of patent 14 years

Int. Cl. D12—09

U.S. Cl. D14—3 A

FIG. 1

FIG. 2

FIG. 3

FIG. 4

FIG. 1 is a perspective view taken from one end of a roof drilling and bolting machine embodying my new design.

FIG. 2 is a perspective view taken from another end thereof.

FIG. 3 is a side view thereof.

FIG. 4 is a top plan view thereof.

I claim:

The ornamental design for a roof drilling and bolting machine, as shown.
